(57) **CLAIM**

(21) Appl. No.: **29/244,720**

The ornamental design for fixing article for floor mat of automobile, as shown and described.

(22) Filed: **Dec. 14, 2005**

DESCRIPTION

(30) **Foreign Application Priority Data**

FIG. 1 is a perspective view of the front, right and top of a fixing article for floor mat of automobile showing our new design;

Jul. 15, 2005 (JP) 2005-020790

FIG. 2 is a front view thereof;

(51) LOC (8) Cl. **08-08**

FIG. 3 is a rear view thereof;

(52) U.S. Cl. **D8/382**

FIG. 4 is a top plan view thereof;

(58) **Field of Classification Search** D8/382-383;

FIG. 5 is a bottom view thereof; and,

24/351, 363; 16/4

FIG. 6 is a right side view thereof.

See application file for complete search history.

The elements shown in broken lines are for illustrative purposes only and form no part of the claimed design. And the dot-dash broken lines define the boundaries of the claimed portion and the non-claimed portion.
